ARTHUR S. KNIGHT, OF NEWARK, NEW JERSEY, ASSIGNOR TO WESTINGHOUSE LAMP COMPANY, A CORPORATION OF PENNSYLVANIA.

INCANDESCENT LAMP.

1,125,694.

Specification of Letters Patent.

Patented Jan. 19, 1915.

Application filed April 10, 1909. Serial No. 439,090

To all whom it may concern:

Be it known that I, ARTHUR S. KNIGHT, a subject of the King of Great Britain, and a resident of Newark, in the county of Essex and State of New Jersey, have invented a new and useful Improvement in Incandescent Lamps, of which the following is a specification.

My invention relates to electric incandescent lamps, and particularly to tubular lamps having straight filaments extending from end to end thereof.

The object of the invention is to provide a lamp of the character indicated that shall embody simple and effective means for maintaining the filament thereof taut and out of engagement with the sides of its tubular casing.

The lamp constituting the present invention differs from others heretofore provided in that the filament is divided into a plurality of sections between which are interposed resilient means that permit the filament to expand and contract freely while still maintaining it taut.

The invention consists further in the provision of a specific form of tension device that is adapted to be interposed between the filament sections and that not only introduces the desired degree of resiliency into the conductor system, but also provides a low-resistance connection between the filament sections and serves to partially support the same.

Figure 1 of the accompanying drawing is a side view of a lamp embodying the present invention, and Fig. 2 is an end and sectional view of the lamp on the line II-II of Fig. 1.

Arranged in end to end or series relation within a tubular glass casing 1, and between metal terminal members or caps 2 that are mounted upon opposite ends of the tubular casing, are a plurality of sections 3 and 4 of a filamentous material, such as carbon or tungsten that is adapted to become heated to incandescence upon the passage of electric current therethrough. Interposed between the filament sections 3 and 4 and electrically and mechanically connecting the same, is a tension device 5 consisting of two strips or wires 6 and 7 having reversely bent portions that project laterally from the axis of the lamp and are arranged obliquely or at an-

gles with respect to each other. The reversely bent portions of the parts 6 and 7 engage the sides of the tubular casing and support the filament approximately centrally within the casing and out of engagement with the sides thereof. The part 6 of the tension device is preferably composed of copper or other suitable material having a high degree of conductivity, and the ends thereof are directly connected to the filament sections 3 and 4, thereby providing a low resistance connection between the said filament sections. Since the part 6 possesses but a slight degree of resiliency, and since its pliability increases as it is heated, the part 7 is preferably composed of nickel, or other suitable material which retains its resiliency upon being heated, the ends of the two parts 6 and 7 being mechanically secured together in any suitable manner, as by twisting them together, in order that the resiliency of the part 7 may be utilized to maintain the filament taut. The nickel spring 7 is of such high resistance that, if it were interposed alone between the filament sections, the energy consumed by the lamp would be objectionably increased and the spring would become unduly heated, and for that reason, the low resistance shunt 6 is provided therefor. It follows that the tension device provides a connection of a high degree of conductivity between the filament sections 3 and 4, and that it maintains the filament taut under all conditions, and supports it out of engagement with the sides of the tubular casing.

I claim as my invention:

1. An incandescent lamp comprising a casing, a plurality of filament sections arranged end to end therein, and separate resilient means interposed between adjacent filament sections.

2. An incandescent lamp comprising a casing, a plurality of filament sections arranged end to end therein, and separate resilient means interposed between adjacent filament sections and electrically connecting the same.

3. In an incandescent lamp, the combination with a casing, and a plurality of filament sections arranged end to end therein, of resilient means interposed between adjacent filament sections and comprising a reversely bent conductor of low resistance.

- that is connected at its ends to the adjacent filament sections, and a reversely bent spring attached at its ends to the ends of the reversely bent conductor.
- 5 4. In an incandescent lamp, the combination with a casing, and a plurality of filament sections arranged end to end therein, of resilient means interposed between adjacent filament sections and comprising a reversely bent conductor of low resistance and a reversely bent spring attached together at their ends, the reversely bent portions of the conductor and the spring being disposed at angles to each other.
- 10 5. In an incandescent lamp, the combination with a casing, and a plurality of filament sections arranged end to end therein, of resilient means interposed between adjacent filament sections and comprising a reversely bent conductor of low resistance and a reversely bent spring attached together at their ends.
- 15 6. In an incandescent lamp, the combination with a casing, and a plurality of filament sections arranged end to end therein, of resilient means interposed between adjacent filament sections and comprising two members respectively of high and low conductivity both of which are adapted to engage the casing in order to maintain the filament sections substantially central therein.
- 20 7. In an incandescent lamp, the combination with a casing, and a system of conductors therein comprising a plurality of filament sections arranged end to end, and resilient means interposed between adjacent filament sections, of means carried by the system of conductors for assisting in

supporting the filament, the said means being freely movable within the casing.

8. An incandescent lamp comprising a relatively long tube, a plurality of relatively short filaments axially disposed therein, a spring having the extremities thereof oppositely disposed, each of said extremities being secured to a filament end, and said spring having an axial tension between its extremities thereby maintaining the respective filaments on either side thereof taut.

9. In an incandescent lamp, having a filament comprising sections, adjacent sections of which are electrically connected by means having ends which can approach and recede relative to each other to compensate for the expansion and contraction of the filament; the lamp comprising an element or elements which will permit said ends of said means to recede and cause said ends to approach whereby the expansion and contraction of the filament can be compensated for.

10. An incandescent lamp having a filament comprising sections arranged end to end, adjacent sections of which are electrically connected by means having ends which can move toward and from each other; said lamp comprising an element which will cause said ends to move toward each other and thereby maintain the filament sections under tension.

In testimony whereof, I have hereunto subscribed my name this 9th day of April, 1909.

ARTHUR S. KNIGHT.
